TYING MACHINES FOR PACKAGES AND THE LIKE

Maurice Holford Jones, Birmingham, England, assignor to Leo M. Harvey and Lawrence Harvey, trading as The Harmac Company, Los Angeles, Calif.

Filed Aug. 23, 1955, Ser. No. 530,097

Claims priority, application Great Britain Aug. 26, 1954

4 Claims. (Cl. 100—28)

This invention relates to tying machines for binding packages and the like with a flexible metal element of the kind in which the end portions of the metal element are secured by being twisted together by means of a slotted pinion.

In such machines in forming a loop around the package the end portions of the metal element intersect and continue beyond the point of intersection to grippers which apply tension to the loop before it is tied. The point of intersection occurs naturally at one end of the gripping portion of the slotted pinion as can be seen in Figure 9 of U.S. patent specification 2,307,219. With round wire as the metal binding element the crossing of the wire is largely absorbed in the twist formed by the rotation of the slotted pinion but, especially with oval wire or a narrow band tying element, formed for example by flattened wire, can result in a defective tie. Except where the context requires otherwise the term "wire" is used in this specification for convenience to refer to metal binding elements of wire of round, oval, flattened or other section or strip.

It is an object of the present invention to provide means by which this intersection is caused to occur at a point away from the slotted pinion and the overlapping end portions of the wire which are to be twisted together. The intersection of the wire does not interfere with the formation of a proper tie and all the twists in the tie are then formed by rotation of the slotted pinion.

It is a further object of the invention to arrange the wire so that the position of the point of intersection is determined by a finger located to one side of the slotted pinion and so arranged that overlapping portions of the wire are brought into position on opposite sides of the finger either during the formation of the loop or by movement of the finger.

A still further object of the invention is to arrange the wire so that the finger is moved into position in the path of the wire being trained around the object after re-threading of the tie-forming means, to lie between the intersecting wire.

Yet a further object of the invention is to provide for the positioning of the finger in the path of the wire being trained around the object by engagement with the wire being re-threaded in the tie-forming means.

Another object of the invention is to provide that the finger engages the free end portion of the wire during re-threading of the slotted pinion and deflects it towards the object being tied and is engaged by the loop while the wire is being trained around the object being tied and deflects it away from the object being tied.

It is yet another object of the invention to provide an automatic tying machine for training a loop of flattened wire or band around an object and securing the ends by twisting them together in superposed face-to-face relationship.

Further objects of the invention will become apparent from the ensuing description of an embodiment of the

2

invention in a tying machine of the kind disclosed in Patent 2,307,219 but which is given by way of example only and with reference to the accompanying drawings in which:

5 Figures 1 and 2 are respectively a plan and fragmentary elevation of the modified parts of the tying machine according to U.S. Patent 2,307,219.

Figure 3 is a perspective view of the right hand gripper shown in Figures 1 and 2.

10 Figures 4 and 5 are an elevation, partly in section, and a plan of the gripper shown in Figure 3.

Figure 6 is an enlarged view partly in section of the tying machine showing a completed tie.

15 Figure 7 shows a modified separator for the overlapping wire ends.

Figure 8 shows a finger which appears near the left-hand gripper in Figure 2.

20 Figures 9 to 13 are fragmentary views taken in a direction looking to the right in Figure 2 of modified components illustrating stages in their operational sequence.

The modification of the machine disclosed in Patent 2,307,219 which is illustrated in the present specification enables packages to be tied with flattened wire that is to say wire which is initially of circular cross-section but is 25 subsequently rolled into narrow strip with smooth rounded edges. The general construction and operation of the modified machine is similar to that of the machine of Patent 2,307,219 to which reference may be made for details of unmodified parts. Wherever appropriate, 30 parts of the modified machine in the present specification bear the same reference numerals as the corresponding parts in U.S. Patent 2,307,219.

Both the basic machine and the machine modified in accordance with the present invention comprise generally

35 a supporting frame 10, a ring 11 rotatably mounted on the frame 10, wire training means 12 on the ring 11 engaging a wire W to wrap or train the wire about an object or package B when the ring is rotated, gripping means 14 and 15 for gripping the wire W, tie-forming means 16 between the gripping means 14 and 15 operable to twist or form a tie in the wire W, means 17 for separating the wire W during the tie-forming operation and for ejecting the completed tie from the means 16, means 18 for shifting and controlling the gripping means 14 to tension the wire W on the object preparatory to the tying operation and to re-thread the wire W at the completion of the tying operation.

40 Additionally the modified machine comprises finger mechanism 300 to be interposed between the free end of the wire held by the gripping means 14 and the adjacent portion of the loop to locate the crossover of the wire at a point outside the slot of the tie-forming means 16, and fork members 301 on each side of the tie-forming means 16 to hold the ends of the overlapping portions of 45 the loop closely together at each end of the twisted tie and to co-operate with the separating means 17 with which they co-operate to sever the free wire parts at the ends of the tie.

46 The finger mechanism 300 comprises a member 302 pivotally mounted about an axis parallel to that of the tie-forming means 16 by a pin 303 on a part 304 rigid with the supporting frame 10. A forward extension 305 on the member 302 projects generally tangentially to a circle centred on the pivotal axis of the member 302. When the member 302 is unrestrained, this extension 305 is downwardly as well as forwardly inclined, occupying the position shown in Figure 9. Forward and downward movement is limited by the engagement of a 50 tail 306 of the member 302 with a shoulder on the part 304. From this forward position the member 302 is mov-

able to the position shown in Figure 10 in which the extension 305 is substantially horizontal.

A shoulder 307 projecting at the root end of the extension from the radially outward side is parallel but rearwardly staggered or rebated with respect to the forward edge 308 of the portion of the member 302 immediately below the extension in order to displace the intersecting wire portions so that they can pass each other edge to edge without twisting as shown in Figure 8. The forward edge 308 forms in effect a shoulder projecting from the radially inward side of the extension near the root.

The wire-receiving slot 158 of the slotted pinion 157 has a rather more widely flared mouth for flattened wire than is normal for round wire and its width is somewhat greater than the double thickness of the wire in order to receive the overlapping portions in superposed face-to-face relationship as shown in Figure 11 and to allow some freedom of movement but naturally this width of the slot is very much less than the width of the wire in order to be able to twist the overlapping wire portions together.

In the machine described in Patent 2,307,219 the separating means comprises separators 170 on each side of the slotted pinion 157 for insertion between the ends of the overlapping wire portions to provide reaction members against which the wire is twisted by the slotted pinion. The separators also have cutting edges which shear the wire against fixed cutting blades when the separators are retracted. In the machine modified in accordance with the present invention and for use with flattened wire the separators 170 are retained to sever the wire on completion of the tie but instead of shearing the flattened wire against fixed blades, the cutting edges co-operate with shear edges 313 of the fork members 301 which are slidably mounted in a manner similar to the separators 170 and are coupled together by a yoke 309 and operated by cams 310, 311 mounted on the shafts 76 and 78 respectively to advance the separators 170 into engagement with the overlapping parts of the wire and subsequently retract them.

The fork members 301 perform the function of reaction members previously performed by the separators 170 and for this purpose limbs 312 of each fork are widely displayed at the ends to provide a lead to engage the ends of the overlapping wire portions as the fork is advanced and guide the overlapping portions into a narrower slot 314 between the limbs which grips them closely together while the tie is formed.

The separators 170 taper laterally towards the adjacent fork member 301 (Figure 7) so that, as shown in Figure 2, the overlapping wire portions can lie close together to pass through the slot 314 but are more widely separated on the sides remote from the tie-forming means 16. Wire is cut by shearing action between upright edges 315 on the separators 170 and the shear edges 313 on the fork members upon retraction of the separators 170.

Since the point of intersection of the loop ends of the wire occurs away from the twister pinion, therefore, as can be seen in Figure 2 on the lefthand side of the tie-forming means 16, it is the upper of the overlapping portions which must be cut while on the right-hand side it is the lower portion. The separators are shaped accordingly, that on the left-hand side having its upright edge 315 extending upwardly as shown in Figure 7, that on the right-hand side downwardly.

The second gripper 15 is also modified. Instead of having a movable jaw which grips the wire between its forward face and a rearward face on the body it has a jaw 316 (Figures 3 and 4) pivoted to the body 100 of the gripper by a pivot pin 317 and grips the wire between an upper face 318 and a downward face of an anvil insert 319 fixed to the body 100 by screws 320. The wire is held with its major axis horizontal. A com-

pression spring 321 housed in aligned sockets in the body 100 and movable jaw 316 normally urges the jaw 316 to the open position shown in chain-dotted lines in Figure 4. For closing the jaw to grip the wire a link 5 116 (Figures 2 and 5) is longitudinally movable by a bell crank 119 against the action of a spring 70, as described in Patent 2,307,219, and is provided at the end remote from the spring 70 with a roller 322. Parallel surfaces 323 on the jaw 316 and 324 on the body 100 are engaged by the roller 322 when the link 116 is moved towards the gripper 15 and separated to move the jaw 316 to the closed position.

The sequence of events in the operation of the modified machine is similar to that of the machine of Patent 2,307,219 and is briefly as follows. In the rest position of the machine the free end of the wire is held in the gripper 14 and has already been threaded into the slot 158 of the pinion 157 through which it extends to the wire training means 12. A box B to be tied is placed in 15 position on the supporting frame 10. The operator starts the machine by a manual control. The ring 11 is first caused to rotate once about its axis causing the wire-training means 12 to form the wire W in a loop around the package B. Up to this point the operation of 20 the machine is the same as that of Patent 2,307,219. As the ring nears the end of its single revolution the wire W at the supply end of the loop is brought against the underside of the extension 305 causing the extension to deflect the wire and causing the crossover of the ends 25 of the loop to occur at a point X (Figure 2) between the gripper 14 and the finger mechanism 300. The supply end of the loop enters the downwardly directed slot 158 and is superposed on the wire portion previously inserted. The overlapping portions then lie face-to-face as shown 30 in Figure 11. The operation of the machine then continues as in Patent 2,307,219. Upon completion of the single revolution of the ring 11 the tie-forming operation is caused to begin. The second gripper 15 is advanced 35 just before the ring 11 completes its revolution and receives the supply end of the wire between its open jaws which are then closed as already described to grip the wire. The first gripper 14 holding the free end of the wire is then moved to the left (Figure 2) by its controlling and shifting means 18 to increase the tension of the 40 loop and the separators 170 are advanced between the ends of the overlapping portions of the wire. At this point a difference in operation occurs in the modified machine for the separators 170 are immediately followed by the fork members 301 which are advanced to hold 45 the overlapping ends closely together adjacent the ends of the slotted pinion. Thereafter normal operation is resumed, the tie is formed by twisting the overlapping wire portions by the rotation of the slotted pinion 157. The ends of the loop projecting from the tie are severed 50 by retracting the spreaders 170 and the completed tie ejected from the slot 158, which at that stage is horizontal and has its opening forwards, by advancing the spreaders again.

The tying of the package B is now completed but the 55 wire supply has to be re-threaded in the tie-forming means 16 before the machine comes to rest. This operation is identical with the re-threading of the slotted pinion in Patent 2,307,219 except for the effect of the finger mechanism 300. The movable gripper is opened to release the wire tailing, swung forwards by angular movement of the rod or carrier 86, shifted bodily to the right across the front of the tie-forming means 16 by axial movement of the carrier 86 and swung rearwardly into position immediately to the left of the gripper 15 so that 60 its open jaws straddle the newly cut end of the wire supply.

The gripper 14 is then caused to close and grip the wire and the gripper 15 to open and release it whereupon the gripper 14 is again swung forwardly, returned to the 65 left across the front of the tie-forming means 16 and

swung rearwardly again into its initial position. It is during this rearward swinging movement that the finger mechanism 300 has its effect. Upon ejection of the previously completed tie and the release of the tailing the finger mechanism is no longer restrained and therefore drops forward to the position shown in Figure 9. When the gripper 14 swings rearwardly the wire it holds engages the upper surface of the extension 305. The wire is deflected by the upper surface of the extension 35 until the wire engages the upper forward edge 307. As the gripper 14 swings rearwardly the finger member 302 is also swung rearwardly by the wire which it assists to enter the now downwardly directed slot 158. When the gripper 14 reaches its normal position the finger member 302 has reached the position shown in Figure 10 with the extension 305 horizontal ready to receive the supply end of the loop, deflect it downwardly and locate the position of the cross-over upon the next wire-training operation as previously described.

After ejection of the tie the spreaders 170, fork members 301 and the right-hand gripper 15 are retracted in readiness for the next wire-training operation.

Since the free ends of the tie and the adjacent portions of the loop are held closely together by the fork members 301 as shown in Figures 6 and 13 and these ends are cut off close to the face of the fork members 301, the cut ends lie safely, close against the adjacent portions of the completed loop.

I claim:

1. In a tying machine, for tying a wire loop trained about an object, a bodily movable first gripper for holding the free end of the wire, a second gripper, tie-forming means spaced between the grippers, severing means for severing the tie from the wire portions held by the grippers, means for operating and bodily moving said first gripper to receive and grip said newly cut portion presented by the second gripper and to return to its initial position to rethread the tie-forming means for the next operation, the final movement of said first gripper means operable to move said newly cut portion laterally toward said tie-forming means, and finger means between said tying means and the normal position of said first gripper for engaging and deflecting said newly cut portion towards said object during rethreading of the tying means and for being engaged and causing deflection of said loop away from said object while the loop is being trained around the object, said finger means comprising a member pivotally mounted for angular movement about an axis transverse to said lateral direction of movement of the wire upon the return of the first gripper to its initial position and having an extension generally tangential to a circle centred upon the pivotal axis of the finger means, opposite sides of which extension are engageable by the overlapping wire portions, and further having shoulder means projecting from the radially outer end of said opposite sides for engaging said newly cut portion moved by the first gripper returning to its initial position and for causing said newly cut portion to swing said extension into position for engagement of the radially inward of said opposite sides with the loop.

2. A tying machine comprising in combination, wire-training means for forming a loop of flattened wire about an object to be tied, tensioning means for tightening the wire loop about the object, tie-forming means for twisting together superposed overlapping ends of the wire loop, fork means on each side of said tie-forming means for anchoring the overlapping ends against twisting, separating means adjacent each of said fork means for separating said overlapping ends and for co-operating

with said fork means to cut off excess wire projecting from the ends of the completed tie, means for projecting the fork means into engagement with the overlapping ends of the wire loop before the commencement of the tie-forming operation and for retracting the fork means upon completion of the tie-forming operation, means for projecting said separating means into engagement with the overlapping ends of the wire loop before the commencement of the tie-forming operation, for partly retracting said separating means to cut the wire, for advancing the separating means again to eject the completed tie from the tie-forming means and for retracting the fork means upon completion of the tie-forming operation.

- 15 3. A tying machine for tying a flat metal band about an object comprising in combination a bodily movable first gripper for holding the free end of the band, band-training means for training the band in a loop about the object, a second gripper for anchoring the supply portion of the band on completion of the loop, means for supporting the first gripper for bodily movement along an axis and for turning about said axis, means for bodily shifting said first gripper to tension the band on the object preparatory to the tying operation and while the 20 supply portion of the band remains fixedly anchored in the second gripper, tie-forming means spaced between the grippers for twisting together superposed overlapping ends of the band loop, means for severing the tie from the supply portion of the wire, means operable at the 25 completion of the tie for opening the first gripper, for swinging the first gripper about said axis, for moving the first gripper along said axis, for swinging the first gripper about said axis to the second gripper, for swinging the first gripper away from the second gripper, for 30 moving the first gripper back along said axis and for swinging the first gripper back to its initial position, and means for actuating the first gripper while at the second gripper to receive the newly cut free end of the band from the second gripper so that the wire is rethreaded in 35 the tying means when the first gripper swings back into its initial position, finger means between said tie-forming means and said first gripper angularly movable about a pivotal axis parallel to said first mentioned axis for engaging the band when the first gripper swings back into its 40 initial position and for being moved by the band into a position in the path of the band being trained about the object such that a portion of the completed loop engages the side of the finger means opposite that in contact with the newly cut end, and are held apart by said finger 45 means to prelocate the cross-over points of said band portions at one side of said tie-forming means.
4. A tying machine according to claim 3 wherein the finger means comprises a member having an extension generally tangential to a circle centred on the pivotal axis of the finger means, opposite sides of which are engageable by the intersecting band and parallel but staggered shoulder means extending from the opposite sides at the root of the extension for locating the bands to pass one another edge-to-edge without twisting.
